UNITED STATES PATENT OFFICE.

LEONARD ECKERT, OF RANCHER, MONTANA.

WIRE STRETCHER AND FASTENER.

No. 906,122.

Specification of Letters Patent.

Patented Dec. 8, 1908.

Application filed December 14, 1907. Serial No. 406,520.

To all whom it may concern:

Be it known that I, LEONARD ECKERT, a citizen of the United States, residing at Rancher, in the county of Rosebud and 5 State of Montana, have invented a new and useful Wire Stretcher and Fastener, of which the following is a specification.

This invention has relation to wire stretchers and fasteners especially adapted for use 10 in fence construction and it consists in the novel arrangement of its parts as hereinafter shown and described.

The object of the invention is to provide a means for stretching the line wires of a fence 15 which means is permanently attached to one of the fence posts and is so arranged that when operated it will exert a pull on the wire extending beyond the opposite sides of the post.

20 In the accompanying drawing:—Figure 1 is a perspective view of a post equipped with the wire stretcher. Fig. 2 is a top plan view with parts in section of a winding spool forming a part of the wire stretcher. Figs. 25 3, 4 and 5 are side elevations partly in section of several forms of means for attaching the wire stretcher to the post.

The wire stretcher consists of the members 1, 2 and 3 each of which is provided with a 30 screw-threaded end 4 which is adapted to enter the post of the fence. The outer portions of the members 1, 2 and 3 are rectangular in cross section and may be operated upon by a wrench when the members are screwed 35 into position upon the fence post. The member 1 is provided with a rectangular opening 5. The member 2 is provided with a rectangular opening 6 with the projecting parallel flanges 7 having perforations 8. 40 The member 3 is provided with the parallel flanges 9 having perforations 10. The shafts 11 are squared at their ends as at 12. The member 1 is located near the base of the post, the member 2 at an intermediate portion 45 of the post and the member 3 in the vicinity of the top of the post.

As illustrated in Fig. 1, the flanges 7 of the member 2 are opposite the opening 5 of the member 1 and the opening 6 of the member 2 is opposite the flanges 9 of the member 3. Thus in placing the shafts 11 in position upon the said members the lower squared ends of the said shafts are first inserted in the

openings 5 and 6 of the members 1 and 2 respectively, then, the upper squared ends of 55 the said shafts are passed laterally between the flanges 7 and 9 of the members 2 and 3 respectively and are held therein by the cotter pins 13 which are passed through the perforations 8 and 10. By reason of the fact 60 that the end 12 of the shafts 11 are squared the said shafts are held against rotation in the said members. Each shaft 11 is provided along its length with a series of perforations 14 and the spools 15 are rotatably 65 mounted upon the said shaft. The upper ends of the spools 15 are squared as at 16, which portions are adapted to be operated upon by a wrench when the spools are turned. Immediately below the squared 70 portions 16 each spool is provided with a relatively broad flange 17 having transverse perforations 18. The lower ends of the spools 15 are provided with flanges 19 and the hooks 20 are integral with the spools and 75 are located between the flanges 17 and 19. The hooks 20 on each spool are disposed substantially in parallel relation to each other and consequently one or the other of the said hooks may be engaged with the line wire 80 irrespective of the directions in which the spool may be turned. To tighten the line wire 21 it is laterally caught into engagement with one of the hooks 20 and the spool 15 is turned, whereby the line wire is wound upon 85 the same and is stretched from opposite directions toward the post upon which the spool is mounted. When the wire is sufficiently drawn a pin 22 is passed through one of the perforations 18 and one of the perforations 14 in the shaft 11, whereby, the said spool is fixed with relation to the said shaft. The spools upon the same shaft 11 are held at proper distances apart by the pins 23 which also pass through the perforations 14 95 and prevent the said spool from moving longitudinally of the said shaft.

Having described my invention what I claim as new and desire to secure by Letters-Patent is:—

100 In combination with shafts having rotatable wire engaging members located thereon, supporting members for the shafts adapted to be arranged in alinement with each other, the upper and lower members having shaft 105 receiving openings of different configuration

and which are adapted to retain the shafts against rotation and the intermediate member having shaft receiving openings the upper one of which is similar to the opening in the lower member and the lower one of which is similar to the opening in the upper member.

In testimony that I claim the foregoing as my own, I have hereto affixed my signature in the presence of two witnesses.

LEONARD ECKERT.
